UNITED STATES PATENT OFFICE.

DE WANE B. SMITH, OF DEERFIELD, NEW YORK.

NURSING BOTTLE AND NIPPLE.

956,741.

Specification of Letters Patent.

Patented May 3, 1910.

Application filed February 24, 1908. Serial No. 417,289.

To all whom it may concern:

Be it known that I, DE WANE B. SMITH, of Deerfield, in the county of Oneida and State of New York, have invented certain new and useful Improvements in Nursing Bottles and Nipples; and I do hereby declare that the following is a full, clear, and exact description thereof, which will enable others skilled in the art to which it appertains to make and use the same, reference being had to the accompanying drawings, and to the characters of reference marked thereon, which form part of this specification.

15 The object of the present invention is to provide a nursing bottle which is very accessible for cleaning, and the removable nipple closure portion of which is of such construction that it will remain securely in place without requiring a separate fastening device, while the nipple itself cannot be easily forced down into the bottle.

20 In the drawings Figure 1 is a perspective view of a nursing bottle embodying the present invention. Fig. 2 is a vertical central section of the upper end of the bottle and the nipple. Fig. 3 is a plan view of the nipple, and Fig. 4 is a sectional view, similar to Fig. 2, of a modified form of construction.

25 Referring to the drawings, 1 indicates the bottle, which is preferably of the general cylindrical form and open substantially to its full diameter at the upper end, and provided at the upper end with an outwardly standing flange 1^a. Just below the flange 1^a, and closely adjacent to the open mouth of the bottle, is an annular groove. The nipple closure 2 consists of an elastic head or 30 diaphragm portion 2^a having a flanged and beaded edge 2^b, the beaded flange encircling the upper end of the bottle and engaging under the flange 1^a of the latter by virtue of the groove adjacent to said flange, while 35 the head 2^a is strained or placed under tension across the mouth of the bottle, lying, when so stretched, in a substantially true plane, across the open mouth of the bottle. Beyond the head portion 2^a the walls of said 40 nipple closure converge inwardly, or are arched toward one another, to provide an intermediate or neck portion 2^c, which is preferably provided with thickened and strengthened portions, as shown, and which 45 terminates in a hollow, pliable teat or nipple portion 2^d. At the point A the nipple 50

will be provided with the usual outlet opening or openings.

It is evident that the nipple can be placed on the bottle by stretching the head 2^a and the beaded flange 2^b into position across the mouth of the bottle, so that said beaded flange will rest under the flanged edge 1^a thereof and be received in the annular groove adjacent to the mouth of the bottle, in which 60 position it serves as an efficient closure which will remain securely in place; while the nipple or teat portion will be maintained in a normally erect position. When suction is applied to the teat there exists more or less 65 of a tendency to form a vacuum in the body of the bottle, and the head 2^a will have a tendency to become more or less deflected inwardly. The thickened arched or outwardly converging walls of the intermediate 70 portion 2^c form a self-bracing structure which obviates any tendency on the part of the teat to turn inside out through an opening in the head 2^a, this action being assisted by the thickened portions of its 75 walls when these are employed. The thickened walls, which preferably extend from the head portion 2^a to a point about half way up to the end or top of the nipple or teat, assist the teat in recovering its normal 80 form when the suction is relieved and when the rarefaction in the bottle is relieved.

It is evident that the nipple can be readily removed by slipping the beaded edge 2^b out from under the flange 1^a, and that when removed the interior of the bottle is very accessible for cleaning and the interior of the 85 nipple is also equally accessible.

The modified form of construction in Fig. 4 differs from that shown in the other figures mainly by having the base of the teat located at an opening provided in the side of or eccentrically to the head 2^a, instead of centrally, as shown in the other figures. This eccentric arrangement of the teat or nipple, 90 which is preferably inclined inwardly, as shown, is a convenient one, as it takes the place of a curved bottle, and the milk will run out easier than it does with the nipple 95 in the center of the closure.

100 Other modifications and changes than those shown may, of course, be made.

The elastic closure for the bottle will preferably be of rubber, as is usual with devices of this kind; and will be of such size, relative to the open mouth of the bottle, that the head or diaphragm portion 2^a thereof 105

will be under considerable tension when the closure is placed in position on the bottle. Such tension of the portion 2^a of the closure, extending at a right angle, or substantially so, to the plane of the depending beaded flange 2^b, will cause the said beaded flange to hug the flange 1^a on the bottle so tightly that the closure will be securely retained in place without requiring a special fastening device; while the upwardly converging bracing walls at the base of the teat or nipple portion of the closure will resist any tendency of the said teat or nipple portion to be forced downward, or turned inside out, within the mouth of the bottle, a difficulty which has been more or less experienced with the closures heretofore provided for wide-mouthed nursing bottles.

By reference to the drawings it will be seen that the head or diaphragm portion 2^a, immediately above and at a right angle, or substantially so, to the flange 2^b, is much thinner than said flange, and is also thinner than the upwardly converging lower portion 2^a of the teat or nipple immediately above said diaphragm. This relatively thin diaphragm portion of the closure, when under tension, is very elastic, and, when suction is applied to the nipple, said head or diaphragm portion will have a vibrative or pumping action which will facilitate the nursing operation, as will be understood.

What I claim as new and desire to secure by Letters Patent is:

1. A nursing bottle comprising a receptacle having an open top or mouth equal in diameter to the body of the receptacle, or substantially so, and having a flange at its top, combined with a closure consisting of an elastic body having a beaded or thickened flange adapted to engage the top of the re-

ceptacle beneath the said flange on the latter, said closure having a relatively thin diaphragm portion immediately above and contiguous to the said beaded, or thickened flange, said diaphragm portion extending approximately at a right angle to said beaded or thickened flange, and a nipple portion immediately above said diaphragm portion and having upwardly converging walls. 45

2. A nursing bottle comprising a receptacle having an open top or mouth equal in diameter to the body of the receptacle, or substantially so, and having a flange at its top, combined with a closure consisting of an elastic body having a beaded or thickened flange adapted to engage the top of the receptacle beneath the said flange on the latter, said closure having a diaphragm portion immediately above the beaded flange thereon, 50 and a nipple portion extending upward from the said diaphragm portion and having upwardly converging walls, said converging walls being thickened from said diaphragm portion to a point about half way to the end or top of the nipple. 55

3. A closure, for wide-mouthed nursing bottles, consisting of an elastic body having at its base a beaded or thickened flange to engage a flange on the bottle, a diaphragm 70 portion immediately above and approximately at a right angle to said beaded flange, and an eccentrically arranged nipple portion extending upward from said diaphragm portion. 75

In witness whereof, I have affixed my signature, in presence of two witnesses, this 11th day of Feb. 1908.

DE WANE B. SMITH.
